UNITED STATES PATENT OFFICE.

STEPHEN H. BROOKS, OF CLEVELAND, OHIO.

DESIGN FOR A GAS-SHUT-OFF PULL-BOX.

46,660.

Specification for Design.

Patented Nov. 24, 1914.

Application filed July 28, 1914. Serial No. 853,717. Term of patent 14 years.

To all whom it may concern:

Be it known that I, STEPHEN H. BROOKS, a citizen of the United States, residing at Cleveland, in the county of Cuyahoga and State of Ohio, have invented a new, original, and ornamental Design for a Gas-Shut-Off Pull-Box, of which the following is a specification, reference being had to the accompanying drawing, forming part thereof.

The figure is a perspective view of a pull box showing my new design.

I claim:

The ornamental design for a gas shut-off pull box, as shown.

STEPHEN H. BROOKS.

Witnesses:

WILBUR H. BROOKS,
HERBERT A. STOWE.
